KEY CASE

Nick J. Duyn, Tucson, Ariz.

Application May 20, 1946, Serial No. 671,097

4 Claims. (Cl. 70—456)

1

This invention pertains to key cases and has for its objects,

First, the provision of a key case wherein the keys are pivotally fastened within a case body and resiliently held in closed position by frictional engagement with the sides of the case;

Second, the provision of a key case folded of a flat metal stamping so as to provide a flat package wherein key handles may be pivotally held within one end, and the blades retained by compression and friction within the other end together with spring means for normally forcing the keys to open or presented position when released from said compression;

Third, the provision of a structure between the blade holding ends of the case above mentioned whereby the key blades may be released from said retaining compression by pressure simply applied by the fingers to the rear portion of the case.

Other objects will appear hereinafter.

I attain the foregoing objects by means of the device illustrated in the accompanying drawings in which—

Figure 1 is a plan view of a key case embodying my improvements;

Figure 2 is a side elevational view of the back thereof;

Figure 3 a side elevation of the front;

Figure 4 a plan view with the face sectioned off showing interior construction;

Figure 5 is an elevational view of the blade holding end showing details of the retaining and releasing mechanism, and

Figure 6 a section taken in line 6—6 of Figure 1.

Similar numerals refer to similar parts in the several views.

The case body 2 is folded from a sheet metal blank to form a flat package like container having a rounded end portion 3 substantially conforming to the shape of a key head and a rectangular shaped blade retainer end portion 4.

Keys 5 and 6 are pivotally secured by a bolt 7 passing thru holes 8 in the head portion and thru holes customarily made in the handle portion.

The parts of the case are proportioned so that it substantially encompasses the keys and the blades of the keys will be enclosed between plates of the blade retainer end 4.

In folding the blank from which the case is formed a web 10 is provided joining the top plate 11 and the bottom plate 12 along the back. This provides longitudinal rigidity for the body and acts as a definite spacing member between the plates. The web 10 is made sufficiently wide

2

to provide adequate room for the key handles within the rounded end portion 3, while the material is joggled or bent inward at 14 toward the blade ends to bring the plate portions closer together for adequate gripping of the key blades by spring pressure.

A spring 15 is attached to web 10 and extends arcuately inward to contact the sides of the keys at a point inward from bolt 7. The spring is shaped so that normally it tends to force keys out of the closure of the end part of the case to the position indicated by dotted outline 16. In this position the flank of either key may be easily and conveniently grasped by the user and the key cleared for insertion into a lock. The keys may be said to be normally urged or biased to exposed or open position by this spring.

When the keys are rotated into closed position the blades are guided into place by the outwardly flared entrance lips 17 and retained by the beads 18 which parallel the top or entrance edges of this part of the case.

Inward swinging movement of the keys is limited by a tab 20 punched and bent upward from plate 12.

Inwardly extending lips 19 are formed along the rear edges of the blade holding portion of the case body. These provide rigidity for these rear edges as well as smooth finish.

30 Beads 18 along the inner face of the forward edges are formed by inward creases just behind the flared lips 17. They provide a retaining means for key blades within the end 4 and enhance retention in addition to the friction provided by the inherent spring pressure of the walls of the end portion 4.

35 Due to the construction above explained it will be apparent that the handle portions of the keys are held in the rounded portion 3 of the case body, free to rotate, while due to the joggles 14, the blades are compressed between the sides of the blade holding portion 4.

Tab 20 is formed by a cut out portion in the lower plate which is bent upward with the upper edge becoming a fulcrum on which the blade retaining portion 4 of the upper plate 11 may be rocked or twisted on a longitudinal axis, as shown by dotted outline 11' by pressure applied at the position indicated by arrows 21. When the bottom or compression edge is compressed, as indicated, the forward or entrance edge of this plate portion 4 is opened and the keys released from frictional engagement with inner faces of the plates or walls and released from the retention of beads 18. The manipulation necessary for re-

lease is very simple and easy since it is only necessary to squeeze the rear edge of the plates between thumb and first finger. All keys swing out together but I have found that the keys may be more easily selected, after their release, by sliding them between the thumb and finger than when they must be selectively or independently released from the case.

Ordinarily the case is made from thin spring metal. However, heavier metal can be used and in this event transverse slots 22 are cut into the material at approximately the juncture between the handle holding area and the blade retaining area. This relieves the metal so that torsional resistance is lessened.

From the foregoing it will be understood that I have provided an easily made simple and effective key case which includes a minimum number of parts. Some of which may be made in modified forms and still remain within the spirit of the invention. Therefore I wish to be limited only by the following claims.

I claim:

1. A key case composed of parallel side walls of spring metal joined by a web shaped to provide a key handle holding area and a blade holding area; a bolt extending thru said handle holding area adapted to retain keys between said walls so they may be swung with the blades between the walls of said blade holding area; a spring attached to said web normally urging said keys outward from said blade holding area; the wall portions of said blade holding area affording mutual resilient compression to retain the blades of keys swung therebetween and having an entrance edge and a compression edge adjacent said web; a tab forming a fulcrum positioned between said blade holding portions of said walls so that compression of said compression edge will open said entrance edge to release key blades engaged therebetween.

2. A key case for flat keys having a body composed of parallel walls of spring metal connected and spaced by a web along the back side thereof, a tightening bolt passing thru an end of said case to rotatively secure keys therein at their handle portions so that they may be swung between the walls at the opposite end of said case body; said walls being inwardly bent to form key blade retaining portions which compressibly retain blades of keys therebetween while the handle portions allow the key handles to swing freely; together with a spring attached to said case normally urging said key blades from between said walls, and an inwardly extending tab formed on the blade holding portion of one of said walls adapted to act as a fulcrum on which the opposite

wall may be torsionally rocked; said wall portions having torsion relieving slots extending transversely therein from each side at approximately the position of the said bends; the said fulcrum being arranged so that compression of the edge of said blades opposite the key blade entrance edge will expand said entrance edges and release key blades therefrom.

3. A key case for a plurality of flat keys arranged side by side formed of spring material side walls substantially encompassing the keys, said side walls being connected at the bottom at one end portion, means for pivotally mounting the heads of the keys in said end portion, means to bias the keys for outward swing through the top of the case on the pivotal mounting for the heads, the remaining portion of the side walls being unconnected and relieved between the connected and unconnected portions for flexibility, said portion of the side walls being spaced less than the width of the plural keys whereby the walls are expanded at the top to receive and hold the key blades when swung therebetween by inherent spring pressure working against the ejecting bias, and an intermediate fulcrum carried by one side wall to permit automatic release of the keys when the side walls are rocked by inward pressure at the bottom portions thereof.

4. A key case for a plurality of flat keys arranged side by side including a single piece of spring material bent to form spaced side walls substantially encompassing the keys, said side walls comprising a connected end portion in which the key heads are pivotally mounted and a flexible unconnected portion between which the key blades are held by inherent spring pressure, spring means to normally urge the key blades from between the flexible side wall portion on the head pivot, and an intermediate fulcrum carried by one flexible side wall to permit automatic release of the key blades for outward swing from the flexible side wall portion of the case when the walls are rocked by inward pressure at the bottom portions thereof.
